UNITED STATES PATENT OFFICE.

JOHN ANDERSON AND FERDINAND BERGENDORF, OF PHILADELPHIA, PENNSYLVANIA.

MECHANICAL CAN-OPENER.

1,326,707.

Specification of Letters Patent.

Patented Dec. 30, 1919.

Application filed April 15, 1919. Serial No. 290,241.

To all whom it may concern:

Be it known that we, JOHN ANDERSON and FERDINAND BERGENDORF, both citizens of the United States, residing in the city and county of Philadelphia, State of Pennsylvania, have invented a new and useful Mechanical Can-Opener, of which the following is a specification.

Our invention consists of a can opener in which provision is made for opening cans of different sizes by means adapting the throw of the blade employed to be adjusted to varying elevations and descent relative to the height of cans to be opened, provision being also made for the employment of blades of different sizes, and the connection of the same to the device without changing the mechanism of the latter.

It consists also of details of construction, as will be hereinafter described.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a can opener embodying our invention. Fig. 2 represents a partial side elevation, and a partial vertical section of a detached portion thereof.

Fig. 3 represents a horizontal section of a portion on line 3—3 Fig. 1.

Fig. 4 represents a horizontal section of a portion on line 4—4 Fig. 1.

Fig. 5 represents a top or plan view of a blade employed.

Fig. 6 represents a perspective view of a blade employed of a different size from that shown in Fig. 1, on a reduced scale.

Similar numerals of reference indicate corresponding parts in the figures.

Referring to the drawings.

1 designates the base of the device, the same having a substantially flat top and being adapted to have cans to be cut supported thereon, and having on the peripheral portion of its upper face spaced apart upwardly projecting lugs 2 which are formed therewith and are adapted as stops to position the can uniformly in position on said base.

Rising from what may be termed the rear of said base is the boss 3 in which is firmly

secured the standard 4, the lugs 2 on the base 1 being adjacent to said standard. 5 designates a sleeve which is slidably fitted on said standard 4 and has formed with or otherwise secured to it the horizontally extending arm 6 whose outer end has attached to it, the vertically extending blade 7 which consists of a segmental piece of metal having on its side terminals a curved cutting edge 8 which extends downwardly from near the top of said terminals to the bottom forming centrally on the latter the point 9 which is adapted to penetrate the top of a can primarily to the complete opening of the can by said cutting edge, the opposite terminals of the blade widening upwardly from said point.

The top of the blade has riveted or otherwise secured to it the segmental ring 10 which forms the head of the blade and reinforces and strengthens the latter, and has therein the openings 10^x to receive screws 10^{xx} which are passed also through openings 10^{xxx} in the arm 6, thus connecting the blade with the latter, the blade thus depending from said arm as its carrier.

11 designates an ear which is secured to the top of the arm 6 and has pivotally connected with it the lower ends of the links 12 whose upper ends are pivotally connected with the operating lever 13 of the device intermediate of the ends of the latter, said lever having its pivotal end mounted on the sleeve 14 which is slidably fitted on the standard 4, and being above the sleeve 5, it having in its wall the set screw 15 whose point is adapted to enter either of the spaced apart recesses 16, in the side of the standard and so retains said sleeve 14 in its adjusted position.

It will be seen that said sleeve 14 occupies its highest position, in Fig. 1, consequently when the lever 13 is raised the link is adapted to elevate the blade above the top of the can occupying the base 1 which can be illustrated of large size. Then the lever is lowered whereby the link forces down the arm 6, the sleeve 5 and with them the blade to the top of the can and causes its point 9 and edges to cut through said top and enter the body of the can, thus penetrating and cutting said top the width of the blade, thus severing a portion of said top from its surrounding portion. Then the lever is raised when the blade emerges from the body of the can.

the can and rises through the incision in the top and above the same. The severed portion of the top may then be bent up and so the can is properly opened so that when it is removed from the base the contents may be poured out, it being noticed that the operation of severing the top has been accomplished in a powerful, rapid and convenient manner.

- 10 For opening cans of smaller size, the screw 15 of the sleeve 14 may be loosened and the sleeve lowered to an adjusted extent when the screw may be tightened and its point enter the lower recess 16 in the standard, thus firmly retaining the sleeve in its newly set position, whereby when the lever is operated the link imparts a shorter throw to the blade, both in its elevation and descent, and so the blade when lowered is adapted to penetrate and cut the top of the small can, the same as in the case of the larger one, it being noticed that the base is adapted to support cans of different sizes and have the stops 2 adjust the cans true and uniformly on the base in line with the bottom point of the blade whereby the cutting of the top of the small can may be accomplished by the operation of the lever, the same as in the top of a large can. A can 30 may be placed on the flat top of the base and moved slidingly against the lugs 2 and so positioned for opening whether the can is of a narrow or wide diameter, the top of any can wide or narrow then being directly beneath the descending point of the blade.

On the side of the upper portion of the blade are the outwardly projecting lugs 17 which when the blade is lowered serve to contact solidly with the unsevered portion 40 of the top of the can around the severed portion thereof, thus acting as stops to limit the descent of the blade 7.

In Fig. 6, we show a blade of smaller size than that shown in Fig. 1, but on a reduced scale, the same having in the ring-like head of said blade openings for the screws that connect the arm or carrier 6 therewith, said openings being adapted to match or register with those in the head of the larger blade, 50 and so when the large blade is removed a small blade may be applied to the arm and secured by said screws 10^{xx} employed.

The sleeve 14 is formed with upwardly extending ears 18, between which the pivotal end of the blade is adapted to ride in its motions, thus guarding said end from side play or thrust and wabbling motions thereof, it being noticed that the pivotal pin 19 of the lever is passed through one of 60 said ears and the pivotal end of the lever and secured in position by suitable means. Then as the sleeve 5 rides on the standard 4 as its guide the blade moves true in its descent and causes a uniform and comparatively smooth cut in the top of the can.

The sleeves avoid slotting of the standard, and so the strength of the latter is preserved.

Having thus described our invention what we claim as new and desire to secure by Letters Patent is:—

1. In a can opener, a can supporting base, a standard rising therefrom, a plurality of slidable members on said standard, one above the other, means on the upper slid- 75 able member for retaining it in a vertically adjustable position on said standard, a blade, a carrier for the latter on the lower slidable member thereof, a lever having its bearings on the upper slidable member, and a link- like member which is pivotally connected 80 with said lower slidable member and said lever.

2. In a can opener, a blade, a plurality of movable members, one above the other, a supporting and guiding standard for said 85 movable members, the lower member forming the carrier for said blade, a lever, the upper movable member forming the bearing for said lever, a link-like pivotal member adapted to connect said carrier and 90 lever and a set screw on said upper movable member adapted to engage said standard for retaining said member in vertically ad- justed position relatively to the required 95 throw of said lever.

3. A can opener, a blade, a sleeve-like car- rier therefor, a standard on which said car- rier is slidable, a can supporting base from which said standard rises, a link-like mem- 100 ber pivotally connected with said carrier, a pivotal lever with which said link-like mem- 105 ber is also pivotally connected, and an ad- ditional sleeve like member on said stand- ard above said carrier adapted to be ad- justably held on said standard and having the pivotal end of said lever mounted thereon.

4. In a can opener, a can supporting base, a standard rising therefrom, a lever, a plu- 110 rality of sleeve like slidable members on said standard one above the other, and a pivotal link-like connection for the lower sleeve-like member with said lever, the upper sleeve-like member having said lever mounted thereon as its bearing.

5. In a can opener, a can supporting base, a standard rising therefrom, a blade, a plu- 115 rality of sleeve-like slidable members on said standard one above the other, an arm on the lower sleeve-like member forming a carrier 120 for said blade, a lever having its mounting on the upper sleeve-like member, and a piv- otal link-like connection for said arm and lever.
